UNITED STATES PATENT OFFICE.

RUBIN BASS, OF BROOKLYN, NEW YORK.

PRESSING-CLOTH.

1,159,156.

Specification of Letters Patent.

Patented Nov. 2, 1915.

Application filed June 7, 1915. Serial No. 32,623.

To all whom it may concern:

Be it known that I, RUBIN BASS, a citizen of the United States, residing at Brooklyn, in the county of Kings and State of New York, have invented new and useful Improvements in Pressing-Cloths, of which the following is a specification.

The general object of this invention is to prolong the life of pressing cloths, usually 10 used in tailoring establishments, so that a material reduction in savings of both the cloth and the expense incident to the purchase thereof may be effected. And to these ends the invention resides in providing the 15 textile pressing cloth with a means for protecting the cloth from direct contact with the pressing iron.

Other objects will appear and be better understood from that embodiment of my invention 20 of which the following is a specification, reference being had to the accompanying drawings forming part hereof, in which:

Figure 1, is a top plan view of my invention 25 with parts shown broken away for the sake of clearness, and, Fig. 2, is a cross sectional view taken on the line 2—2 of Fig. 1, with the parts shown separated.

As shown in the drawings the cloth is 30 formed of a body of textile material 1, and protecting elements arranged so as to prevent direct contact of the body with the pressing iron.

In the present instance the protecting 35 elements are shown in the form of a ply of asbestos fabric 2, and a reticulated body 3. The asbestos is superimposed on the body 1 and is permanently attached thereto by having the edges of the body and asbestos bound 40 with a tape 4 and secured to the body and asbestos by a row of stitching 5. By the employment of a ply of heat insulating material such, for instance, as asbestos, it is obvious that the textile material is prevented 45 from becoming scorched and damaged, which would occur if direct contact between the pressing iron and body were permitted.

In instances where it is desired to prevent the scorching of the asbestos and the adhering of the fibers thereof to the pressing iron, I employ the guard plate or body 3 which in the present instance is shown in the form of a thin sheet of perforated flexible metal superimposed on the ply of asbestos 55 2 and conveniently secured thereto and to the body by means of screws 7 and thumb

nuts 8 which screws pass through a flexible metallic frame 9 arranged on the lower surface and on the margin of the body 1 and through openings 10 in the body 1 and asbestos 2 and through elongated openings 11 in the guard plate or body 3.

In use the material to be pressed is first dampened by sponging or otherwise, and the pressing cloth is then laid thereover. The 60 hot iron is then applied to the guard in the usual manner, the heat from the iron passing through the perforations, asbestos and body into the cloth to be pressed, thus effecting the drying of the same as is done by 65 the usual pressing operation. By the provision of the elongated openings 11 in the guard, it is obvious that any tendency of the guard to buckle, due to the friction between the guard and the asbestos being less 70 than the friction between the material being pressed and the body, will be compensated for by permitting the guard to slide over the surface of the asbestos during the operation of pressing.

What I claim as new is:

1. A pressing cloth comprising a body of textile material and means superimposed on the cloth and attached thereto for protecting the textile material from direct contact 85 with the heating iron, said means being formed of material having greater heat resisting properties than said body.

2. A pressing cloth comprising a body of textile material and means superimposed on 90 the cloth and attached thereto for protecting the textile material from direct contact with the heating iron, said means including a guard formed of a thin sheet of reticulated metal.

3. A pressing cloth comprising a body of textile material and means superimposed on the cloth and attached thereto for protecting the textile material from direct contact with the heating iron, said means including a 100 ply of asbestos and a guard formed of a thin sheet of reticulated metal.

4. A pressing cloth comprising a body of textile material, a ply of asbestos superimposed on the cloth and attached thereto for protecting the textile material, a guard formed of a thin sheet of perforated flexible metal superimposed on the ply of asbestos and means for detachably connecting the metallic sheet to the body and ply of asbestos.

5. A pressing cloth comprising a body of

textile material, a ply of asbestos superimposed on the cloth and attached thereto for protecting the textile material, a guard formed of a thin sheet of perforated flexible metal superimposed on the ply of asbestos, an attaching frame arranged on the lower surface of the marginal edges of the body of textile material and means for detachably

connecting the metallic sheet and attaching frame to the body and ply of asbestos.

In testimony whereof I affix my signature in presence of two witnesses.

RUBIN BASS.
